SPEED CONTROL FOR OUTBOARD MOTOR
BOATS

William E. Gurr, Chelan, Wash.

Application July 15, 1939, Serial No. 284,745

4 Claims. (Cl. 114—145)

This invention relates to outboard motors, and more particularly to an attachment for controlling the speed of the boat, an advantage which is very useful when trolling for fish; and among the objects of the invention is to improve, generally, upon attachments of this character now generally known and used.

The invention together with its objects and advantages will be best understood from a study of the following description taken in connection with the accompanying drawings, wherein—

Figure 1 is a side elevational view illustrating the application of the speed control device to an outboard motor.

Figure 2 is a rear view of the outboard motor with the attachment applied thereto.

Figures 3 and 4 are horizontal detail sectional views taken substantially on the lines 3—3 and 4—4 respectively, of Figure 1.

Figure 5 is a detail elevational view on a large scale showing certain features hereinafter more fully referred to, and

Figure 6 is a detail elevational view of the blades forming part of the attachment.

Referring more in detail to the drawings it will be seen that the speed controlling attachment indicated generally by the reference numeral 5 comprises an attaching plate 6 having formed integral therewith a clamping plate 7 provided as at 8 and 9 to engage about the tubes 10 and 11 forming part of the outboard motor indicated generally by the reference numeral 12.

Hinged to the plate 7 as at 13 is a clamping or retaining plate 14 which at its free end is apertured to accommodate retaining bolts 15 carried by the plate 6 and equipped with wing nuts 16. Thus it will be seen that the attachment may be readily and quickly mounted on the outboard motor.

The plate 6 at the free end thereof is provided with an integral bearing sleeve 17 in which is journaled a hollow shaft 18. The shaft 18 is equipped on the upper end thereof with a stop collar 19, and intermediate its ends with a stop collar w.

Accommodated within the shaft 18 is a shaft 20 that on its upper end is provided with a collar 21. Interposed between the collars 19 and 21 is a washer 22, as clearly shown in Figure 5.

Mounted on the lower end of the shaft 18 to rotate therewith is a speed retarding blade 23 while mounted on the lower end of the shaft 20 to rotate therewith is a supplemental speed retarding blade 24.

Extending from the plate 6 and disposed at

an angle thereto is a guide arm 25 on which is mounted a slide 26.

The slide 26 is provided with a keeper pin 27 that is engageable in a selected one of a series of openings 28 provided in the arm 25 for securing the slide 26 at the desired position of adjustment on the arm 25.

Carried by the slide 26 is a stud 29 which serves as a pivotal connection between the slide 26 and a link 30 that is pivotally connected to an arm 31 formed integral with and extending from the collar 19.

The stud 29 also provides a pivotal connection between the slide 26 and a link 32 that is pivoted to an arm 33 carried by the collar 21.

Interposed between the ends of the links 30 and 32 pivotally engaging the stud 29 is a collar or washer 34.

The stud 29 also serves to anchor to the slide 26 one end of a leaf spring 35, said spring 35 having its end thereof suitably connected with the pin 27 acting to normally urge the pin downwardly into engagement with a selected one of the openings 28.

From the above it will be apparent that sliding movement of the slide 26 on the arm 29 will, through the medium of links 30, 32 be imparted to the shafts 18 and 20 for rotating the shafts in the proper direction to position the speed retarding blades 23 and 24 at the desired angle of adjustment whereby the operator of the motor boat is enabled to control the same from full speed ahead to any desired lower speed, an advantage which is very useful when trolling for fish, and under other circumstances which will readily present themselves to the reader hereof.

Obviously by engaging the pin 27 with the proper opening 28 the blades 23 and 24 will be thereby secured at the desired position of adjustment. Several positions of adjustment for the blades 23 and 24 are suggested by broken and full lines respectively, in Figure 3.

From the above it will also be apparent that the speed control attachment may be easily and quickly applied to and removed from the outboard motor, and when in use will in nowise interfere with the operation of the propeller of the motor.

It is thought that a clear understanding of the construction, utility and advantages of an invention of this character will be had without a more detailed description.

Having thus described the invention, what is claimed as new is:

1. In a speed control mechanism for use with

- an outboard motor, a mounting plate provided with a clamp adapted to engage intermediate parts of an outboard motor, said plate being provided with a bearing, a hollow shaft having 5 an end journalled in said bearing, a second shaft journalled within said hollow shaft, speed retarding blades mounted on the lower ends of said shafts, a guide arm extending laterally from said plate, a slide mounted on said plate, and 10 link means operatively connecting said slide with said shafts for transmitting movement of the slide to the shafts for placing said blades at the desired position of adjustment, and complementary means on said guide arm and said slide for securing 15 the latter in the desired position of adjustment on the guide arm.
2. A speed control attachment for outboard motors, said attachment comprising an attaching plate having an integral clamping plate provided for engaging intermediate parts of an outboard motor, a complementary clamping plate hinged to said integral plate for cooperation therewith for securing said attaching plate to the outboard motor, means for securing the 20 hinged complementary clamping plate in cooperative clamping position with the first named clamping plate, inner and outer shafts journalled at one end thereof on said attaching plate, coaxing speed retarding blades mounted on the free 25 ends of said shafts, collars on the first named ends of said shafts and provided with arms, a guide arm extending at an angle from said attaching plate, a slide on said guide arm, and link members pivotally connecting the arms of 30 said collars with said slide for transmitting movement of the slide to the shafts for simultaneously rotating the shafts in reverse directions relative to one another for positioning said blades at the desired position of adjustment.
3. A speed control attachment for outboard motors, said attachment comprising a body plate having an integral clamping plate provided for engaging intermediate part of an outboard motor, a complementary clamping plate hinged to 35 said integral plate for cooperation therewith for

securing said body plate to the outboard motor, means for securing the hinged complementary clamping plate in cooperative clamping position with the first named clamping plate, inner and outer shafts journalled at one end thereof on 5 said body plate, coaxing speed retarding blades mounted on the free ends of said shafts, collars on the first named ends of said shafts and provided with arms, a guide arm extending at an angle from said body plate, a slide on said guide 10 arm, and link members pivotally connecting the arms of said collars with said slide for transmitting movement of the slide to the shafts for simultaneously rotating the shafts in reverse directions relative to one another for positioning 15 said blades at the desired position of adjustment, said guide arm being provided with a longitudinal series of spaced apertures, and a spring pressed pin carried by said slide and engageable with a selected one of said apertures for securing the 20 slide in the desired position of adjustment on said guide arm.

4. A speed control attachment for an outboard motor having a propeller, comprising a vertically arranged supporting plate, means for detachably connecting said plate to an intermediate part of the outboard motor, a tubular part at the rear edge of the supporting plate forming a bearing, a hollow shaft journalled in the bearing, a second shaft passing through the hollow shaft 30 and journalled therein, arms connected to the upper ends of said shafts, blades connected with the lower ends of said shafts and said shafts holding the blades in rear of the propeller of the motor, a manually operated slide on the supporting plate at the top thereof and links connecting the slide with the arms of the shafts for transmitting movement of the slide to the shafts for simultaneously rotating the shafts in 35 reversed direction relative to one another for positioning said blades at the desired position of adjustment in rear of the propeller for controlling the flow of water therefrom.
